UNITED STATES PATENT OFFICE.

GEORGE J. WELLS, OF ALBANY, NEW YORK, ASSIGNOR TO THE CHICAGO HARDWARE MANUFACTURING COMPANY, OF CHICAGO, ILLINOIS.

DESIGN FOR A DOOR-TRIMMING.

SPECIFICATION forming part of Design No. 18,351, dated May 22, 1888.

Application filed October 23, 1887. Serial No. 253,470. Term of patent 7 years.

To all whom it may concern:

Be it known that I, GEORGE J. WELLS, a citizen of the United States, residing in Albany, county of Albany, and State of New York, 5 have invented certain new and useful Improvements in Designs for a Door-Trimming, of which the following is a specification, reference being had to the accompanying photograph, forming a part thereof and illustrating a perspective view of my design.

The leading feature of my design is a door-trimming provided with a panel angular or curved, having a surrounding border of parallel beads, and at intervals thereon crossed 15 strips or bands.

Referring by letter to the accompanying photograph, A indicates the escutcheon forming a part of a door-trimming, and B the knob forming the remaining portion of said trimming, 20 both of which are provided with a panel, C, surrounded with parallel beads D, having at intervals thereon crossed bands E, which have the appearance of surrounding and binding the beads together. Both of these central panels 25 may be plain and either raised above or sunk below the plane of the beaded border; but, as shown, and by preference, they are ornamented by serrated-edged leaves *a*, raised above the plane of the panel and arranged in any manner desired upon said panel; but in the escutcheon panel, and at the bottom thereof, there 30 may, as shown, be an urn, *b*, holding the leaves in said panel. Between the central panel and

the beaded border there is an inner surrounding plain border, F, which is shown as raised 35 above, but may be depressed below, the plane of the central panel.

While the ornamentation of the central panel and the use of a surrounding plain border between said central panel and the beaded border 40 with its crossed bands are pleasing and sometimes desirable, it would be no departure from the leading feature of my design to ornament the panel F, or to entirely omit said plain border, or to have the central panel plain or provided 45 with an ornamentation substantially differing from the leaves and urn shown and described.

Having described my invention, what I claim, and desire to secure by Letters Patent, is—

1. In a design for a door-trimming, the escutcheon herein shown and described, the same 50 consisting of beads surrounding a central panel and having at intervals cross-bands.

2. In a design for a door-trimming, the knob herein shown and described, consisting of beads 55 surrounding a central panel and having at intervals cross-bands.

3. The design for a door-trimming, consisting of the escutcheon and knob having beads surrounding a central panel provided at intervals with cross-bands, as shown. 60

GEORGE J. WELLS.
